Patented Dec. 17, 1918.

REED BROWN

By Watson E. Coleman

Attorney

UNITED STATES PATENT OFFICE.

REED BROWN, OF CLINTON, ILLINOIS.

BATH-BRUSH.

1,287,628.

Specification of Letters Patent. Patented Dec. 17, 1918.

Application filed April 21, 1917. Serial No. 163,611.

To all whom it may concern:

Be it known that I, REED BROWN, a citizen of the United States, residing at Clinton, in the county of DeWitt and State of Illinois, have invented certain new and useful Improvements in Bath-Brushes, of which the following is a specification, reference being had to the accompanying drawings.

This invention relates to an improved bath brush and has for its primary object to provide a device of the above character embodying a brush head, and simple and effective means for easily and quickly clamping a wash cloth to said head.

It is another and more particular object of the invention to provide relatively movable clamping members extending around the ends of the brush head, the wash cloth being adapted to be disposed over one face of the head and between the clamping members and the ends of the head, and an element pivotally mounted upon the brush head and operatively connected to said members to simultaneously move the same into clamping engagement with the cloth.

It is also an additional object of my invention to provide a device of the above character which is simple and durable in its construction, highly efficient and serviceable in practical use, and capable of manufacture at relatively small cost.

With the above and other objects in view, my invention consists in the novel features of construction, combination and arrangement of parts to be hereinafter more fully described, claimed and illustrated in the accompanying drawing, in which,

Figure 1 is a perspective view illustrating the preferred embodiment of my improved bath brush;

Fig. 2 is a side elevation showing the clamping members in their inoperative positions; and

Fig. 3 is a transverse section taken on the line 3-3 of Fig. 2.

Referring in detail to the drawing, 5 designates a head block, to one face of which a slab or plate 6 of wood, aluminum, or other non-corrosive metal is permanently secured.

50 This plate is of slightly greater dimensions than the block 5 and projects slightly beyond the end and side faces of said block. The opposite face of the block 5 is provided with a longitudinally extending, tapering groove or channel 7, the walls of which are beveled or undercut to receive the inclined

edges 9 of the brush handle 8, said brush handle being of any desired length and suitably curved so that it may be conveniently manipulated in use. 60

10 designates the clamping members, each of which is of U-shaped form and preferably constructed from a wire rod. The medial portions of said clamping members extend across the respective ends of the block 5 while the arms 11 of said clamping members extend longitudinally along the side faces of the block and in relatively opposite directions. These arms are movable through suitable guide elements indicated 70 at 12, which are fixed to opposite sides of the head block.

A wire bail 13 has its end portions disposed upon opposite sides of the head block and pivotally mounted upon the studs or screws 14 which are fixed in the block. To the ends of this bail, the corresponding terminals of the clamping members 10 which are disposed upon the same side of the block 5, are pivotally connected, as at 15, on relatively opposite sides of the pivot 14 and in spaced relation thereto. 75

In the use of the device, the wash cloth is suitably folded and disposed over the face of the slab or plate 6, the end portions 85 of the cloth being inserted between the intermediate portions of the clamping members 10 and the end faces of the block 5. The wire bail 13 is then swung downwardly from the position shown in Fig. 2 of the 90 drawing to the position illustrated in Fig. 1, whereby the clamping members 10 are moved in relatively opposite directions and inwardly toward the ends of the head block 5. Thus, these members are engaged with 95 the wash cloth and tightly clamp the same against the ends of the block. After using the device, the wash cloth may be readily removed by simply forcing the wire bail 13 upwardly to extend the clamping members 100 100 in relatively opposite directions on the block. By means of the present invention, a single one of the brush heads with the clamping device thereon may be provided and used by all members of the family who will supply their individual wash cloths. The brush head may, of course, be made of various sizes, as well as in other forms than that shown in the drawing. The 105 form, construction and relative arrangement of the several parts of the clamping device for the wash cloth may also be con-

siderably modified and it will, therefore, be understood that while I have herein shown and described the preferred construction and arrangement of the several parts, the 5 same are susceptible of many minor changes and I, therefore, reserve the privilege of adopting all such legitimate alterations as may be fairly embodied within the spirit and scope of the invention as claimed.

10 Having thus fully described my invention, what I desire to claim and secure by Letters Patent is:

15 The combination with a brush head, of a U-shaped member pivotally mounted adjacent its ends upon the opposite sides of the head, U-shaped clamping rods having parallel arms slidably mounted upon the sides of the brush head, the arms of one clamping member being disposed out of longitudinal

20 alignment with the arms of the other clamping member, the arms of the respective clamping members being pivotally connected at their terminals to the ends of said U-shaped member at opposite sides of its pivots, the medial portions of said clamping rods being adapted to engage and clamp a cloth against the ends of the brush head at points adjacent the opposite side faces of said head, and the medial portion of said U-shaped member when the rods are in their 25 effective clamping positions extending across one end of the head and frictionally held upon the cloth engaged thereon.

30 REED BROWN.
